INVENTOR:

Perry Frost

UNITED STATES PATENT OFFICE.

PERCY T. FROST, OF EAST LIVERPOOL, OHIO, ASSIGNOR TO PALM, FECHTELER & CO., OF NEW YORK, N. Y., A CORPORATION OF NEW YORK.

DESIGN FOR A PLATE OR SIMILAR ARTICLE.

46,945.

Specification for Design.

Patented Feb. 16, 1915.

Application filed December 23, 1914. Serial No. 878,809. Term of patent 3½ years.

To all whom it may concern:

Be it known that I, PERCY T. FROST, a citizen of the United States, residing at East Liverpool, in the county of Columbiana and State of Ohio, have invented a new, original, and ornamental Design for a Plate or Similar Article, of which the following is a specification, reference being had to the accompanying drawing, forming part thereof.

The figure is a plan view of a plate showing my design.

I claim:

The ornamental design for a plate or similar article, as shown.

PERCY T. FROST.

Witnesses:

ELIZABETH SMITH,
HERBERT A. SMITH.
